UNITED STATES PATENT OFFICE.

DWIGHT F. BOYDEN, OF BOSTON, MASSACHUSETTS.

GOLF SHAFT OR THE LIKE.

Application filed July 31, 1926. Serial No. 126,141.

This invention has relation to golf clubs or the like, being more particularly concerned with a shaft construction especially suitable therefor, and has for its object to 5 provide shafts with which optimum stroking power may be realized, and which will resist undesirable torsional and bending stresses.

This object is attained by constructing the driving or head end entirely of a material 10 particularly adapted for absorbing torsional and bending stresses, and the grip end entirely of a material capable of giving great power to the stroke, and by properly distributing each material intermediate the 15 ends. Preferably, this distribution is such that each material gradually decreases in amount from the end made entirely thereof toward the opposite end made entirely of the other material.

20 Further features and advantages, details and combinations of parts will appear from a more complete description of an embodiment of the invention shown on the accompanying drawings, wherein

25 Figure 1 is a front view of a shaft embodying the present invention.

Figures 2, 3, 4, 5 and 6 are sections on the lines 2-2, 3-3, 4-4, 5-5 and 6-6, respectively, of Figure 1.

30 Figure 7 shows in perspective the shaft assembled with a head.

Referring to the drawings, the shaft as a whole is designated as *s* and as shown tapers as usual from the grip toward the drive or 35 head end. The shaft comprises a core *b* intermediate its ends made of a material particularly adapted for absorbing torsional and bending stress, such as hickory, and which gradually decreases in size from the 40 drive or head end to the grip end of the shaft. A short distance above the drive end portion of the core it is grooved at its sides, preferably along planes *c*, *d*, meeting at right angles to form recesses *r* gradually 45 increasing both in depth and width toward the drive end of the shaft to the point *k* where the core terminates by merger of the grooves. A solid head end portion *a* of circular section and of proper length to 50 absorb bending and torsional stresses is left.

To facilitate cutting, the surfaces of cut *c* and *d* converge sharply toward each other at their lower ends *e*, *f*, as shown in Figure 55 1. Four recesses are formed, producing a core section of cross shape, the wing portions

w of which gradually increase in depth and decrease in width or taper toward the upper end of the core, finally terminating in knife edges at *k*. A series of segmental strips *g* of a resilient or whippy material which will 60 give great power to the stroke, such as bamboo, are cut to fit nicely within the recesses *r*, and are laid in the recesses and secured in place as by glue. The upper portions *p* of the strips extend for the desired 65 distance above the point *k* of the core and are united together to form the substantially solid handle or grip portion *p* of the shaft. Preferably, the inner corners *i* of the strips 70 are slightly rounded off, to prevent contact with the core which might tend to push the strips outwardly by the flexing of the core when under the stresses of use.

As shown in Figure 7, the shaft is assembled with the club head *h*. The assembly 75 is made so that two of the wing portions *w* of the core lie in the medial planes of the shaft and head, and other two lie in a plane at right angles thereto and intersecting the same in the median line of the shaft. Such an assembly is very effective against the 80 stresses of use.

A built-up shaft such as described is not liable to failure, since the driving or head 85 end portion is formed as a solid piece capable of absorbing to the desired extent the stresses of bending and torsion occasioned by a stroke, the upper or grip end is made of material designed to give great power 90 to the stroke, and the two materials are proportioned intermediate its ends in accordance with the distribution of the stresses therealong, and to give the proper "feel" and "life" to the club.

95 Heretofore, built-up or laminated shafts were objectionable, owing to the fact that the glued laminations extended for the entire length of the shaft, and consequently were subjected at the drive or head end to torsional and bending stresses which they 100 frequently could not withstand, and at the same time to give the necessary driving power. Furthermore, the laminations were of such cross-sectional shape that bending 105 or torsional stresses tended to separate them.

In place of hickory and bamboo as materials of construction, other materials having the desired characteristics may be used, such, for example, as ash, satin-wood 110 or iron-wood in place of the hickory, and

black palm, lance-wood, snake-wood or noib-wood in place of the bamboo.

Having thus described an embodiment of this invention, it is evident that it is susceptible of various changes and modifications without departing from its spirit or scope as defined by the appended claims.

I claim:

1. A shaft comprising a driving or head end made entirely of solid material particularly adapted for absorbing torsional and bending strain, and a grip end made entirely of a different material capable of giving great power to the driving stroke, said materials complementally overlapping intermediate the head and grip ends.

2. A shaft comprising a driving end made entirely of material particularly adapted for absorbing torsional and bending strains, and a grip end made entirely of material capable of giving great power to the driving stroke, each material gradually decreasing in amount from the end made entirely thereof toward the other end.

3. A shaft comprising a driving end made entirely of hickory, and a grip end made entirely of bamboo, said materials complementally overlapping intermediate the said ends and each material gradually decreasing in cross-sectional area from the end made therefrom toward the opposite end made of the other material.

4. A shaft comprising a core of material particularly adapted for absorbing torsional and bending stresses and one or head end of which constitutes the drive end of said shaft, and a series of strips of a material capable of giving great power to the stroke laid into said core and gradually increasing in cross-sectional area from a point above one end of the core to a point beyond the other end of the core.

5. A shaft comprising a core having an end portion of circular section and beyond said portion having recesses cut at its sides gradually increasing in size toward the other end of the core, and a series of strips laid and secured in the recesses and extending beyond the end of the core, said core being of a material adapted for absorbing torsional and bending stresses and said strips being of material capable of giving great power to the stroke.

6. A shaft tapering from end to end comprising a core having an end portion of circular section and beyond said portion having four recesses each gradually increasing in depth and width toward the other end of the shaft, and strips laid and secured in the recesses and extending beyond the core to form a handle portion, said core being of a material adapted for absorbing torsional and bending stresses and said strips being of material capable of giving great power to the stroke.

7. A shaft tapering from end to end comprising a core having an end portion of circular section and beyond said portion having four recesses each gradually increasing in depth and width toward the other end of the shaft, and strips the inner corners of which are rounded off, laid and secured in the recesses and extending beyond the core to form a handle portion, said core being of a material adapted for absorbing torsional and bending stresses and said strips being of material capable of giving great power to the stroke.

8. A shaft comprising a core having an end portion of circular section and beyond said end portion grooved out to a section of cross shape and having wing portions which gradually increase in length and decrease in width toward the other end of the core, and strips laid and secured in the grooves and extending beyond the core to form a handle portion, said core being of a material particularly adapted for absorbing torsional and bending stresses and said strips being of material capable of giving great power to the stroke.

9. A golf club comprising a head, a shaft assembled with said head and comprising a core having an end portion of circular section grooved out to a section of cross shape and having wing portions which gradually increase in length and decrease in width toward the other end of the core, two of said wing portions lying in the vertical medial planes of the shaft and head, and the other two lying in a plane at right angles thereto and intersecting same in the median line of the shaft, and strips laid and secured in the grooves and extending beyond the core to form a handle portion, said core being of a material particularly adapted for absorbing torsional and bending stresses and said strips being of material capable of giving great power to the stroke.

10. A shaft comprising a core having an end portion of circular section, and beyond said portion having recesses cut at its sides gradually increasing in size toward the other end of the core, and a series of strips laid and secured in the recesses and extending beyond the end of the core and secured together to form the grip end of the shaft.

11. A shaft for golf clubs, comprising two overlapping and interlocking sections respectively forming the grip end and the head end of the shaft, said sections having longitudinally extending complemental tongues and recesses located intermediate the ends of the shaft.

12. A golf club shaft comprising a core of resilient wood having the portion of its length between its butt end and its waist of cross sectional contour to provide longitudinal faces, and strips of wood possessing a greater degree of hardness than the core

disposed against and united to the said faces, the said strips merging with the surface of the core at the waist of the shaft.

13. A golf club shaft comprising a core 5 of resilient wood having its waist of circular form in cross section and from its waist to its butt end being of cross sectional contour to provide longitudinal faces, and strips of wood possessing a greater degree 10 of hardness than the core disposed against and united to said faces, the said strips being of decreasing width in the direction of the said waist and merging with the surface of the core at the said waist.

15 14. A golf club shaft comprising a core

of resilient wood having the portion of its length between its waist and its butt end of gradually decreasing cross sectional dimensions and of a cross sectional contour to provide longitudinal faces, and strips of 20 wood possessing a greater degree of hardness than the core disposed against and united to the said faces, the said strips decreasing in thickness and width from the butt end of the shaft to the waist of the 25 shaft and merging with the surface of the core at the said waist.

In testimony whereof I have affixed my signature.

DWIGHT F. BOYDEN.
